UNITED STATES PATENT OFFICE.

JAMES W. BONTA, OF PHILADELPHIA, PENNSYLVANIA, ASSIGNOR TO
J. DANIEL EBY, TRUSTEE, OF SAME PLACE.

TELEPHONE.

SPECIFICATION forming part of Letters Patent No. 333,816, dated January 5, 1886.

Application filed September 25, 1885. Serial No. 178,184. (Model.)

To all whom it may concern:

Be it known that I, JAMES W. BONTA, a citizen of the United States, residing at Philadelphia, in the county of Philadelphia and 5 State of Pennsylvania, have invented certain new and useful Improvements in Telephoning, of which the following is a specification.

If the generally-accepted theory that the Reis system or method of the electric transmission of tones involved the alternate breaking and closing of the line-circuit by the transmitter be correct, in that case the known art 10 of electrically transmitting sounds consists of two branches. One branch is represented by 15 the Reis system. The other branch is represented by the Bell system, in which the transmitter never breaks the circuit on which it operates.

My invention relates to the Reis system, 20 considering it as one in which the transmitter habitually alternately breaks and closes the circuit on which it operates. I have found that it is not possible to transmit articulate speech in a commercially practical manner 25 over a line which is alternately broken and closed by the transmitter, as in the Reis system, although other sounds may be successfully transmitted in that way.

The object of my invention is to so improve 30 the Reis system that articulate speech as well as other sounds can be successfully transmitted electrically.

To this end my invention consists in electrically transmitting vocal articulations and 35 other sounds over a line or secondary circuit by electric currents induced by varying as well as breaking the contact between two electrodes in the primary circuit associated with the said secondary circuit.

40 In order that my invention may be clearly understood, I will proceed to describe it as put into successful practice by the apparatus illustrated in the annexed drawings, which is the best for the purpose which I have so far devised, although I have practiced my invention with more or less success by means of differently-constructed apparatuses. I have 45 only illustrated the transmitting apparatus. Any known practical receiving apparatus 50 may be used in connection therewith.

Figure 1 represents a transverse vertical section of an electrical telephonic transmitter, showing a diaphragm-electrode and a loosely-supported and movable electrode, contact pressure-regulating device, and induction-coil 55 with circuit-connections arranged for operation to vary the strength of a battery-current and to break or interrupt the circuit when the diaphragm is vibrated by sound impinging against it, in accordance with my invention. 60 Fig. 2 is a detail elevation of movable electrode and platform or table therefor. Fig. 3 represents a view similar to Fig. 1, showing modified form of platform or table for movable electrode. Fig. 4 is a detail plan of the movable 65 or loose electrode and its supporting platform or table; and Figs. 5 and 6 are detail elevations of the diaphragm and loose or ball electrodes, showing different forms of outer or contact end for the diaphragm-electrode. 70

A represents the transmitter; B, its diaphragm, having, preferably, on its rear side an electrode, C, which is preferably of carbon, and has an outer rounded, tapered, or other suitably-formed end, c, and this constitutes 75 what I call the "diaphragm-electrode," as it is secured to and moves with the diaphragm.

D is the remaining electrode, and for purposes of my invention I prefer to make it of carbon in the form of a ball or sphere, to loosely 80 support it upon an inclined table or platform, E, and to place the diaphragm-electrode, the ball, and table in the battery-circuit, for reasons hereinafterstated. The diaphragm is connected with one pole of the battery L B, the 85 other pole of which is connected with one end of the primary coil of the inductorium I. The table E is connected with the other end of said primary coil. The secondary coil of the inductorium I is a portion of the line-circuit. 90

The platform or table E is suitably hinged or pivoted at its forward end to the sides of the transmitter-case, so as to preferably place the horizontal and vertical axes of the ball as near as may be in line respectively with the 95 longitudinal center of the diaphragm-electrode and with the vertical center of the pivot or hinge connection of the table E, as shown.

This position of the ball in reference to the inclination of the platform serves for the fol- 100

lowing functions: First, to give an initial contact-pressure between the electrodes which is stable enough to maintain contact between them part of the time while the diaphragm is 5 vibrating under the influence of sounds, but as the electrode D is a ball, and has a rolling motion on the table E as the diaphragm vibrates, such contact-pressure is not stable enough to prevent the ball, under the influence of the resultant motion imparted to it by 10 the diaphragm, from receding or parting from the diaphragm-electrode during or at the end of an impulse by the latter; and, second, to form a wedge-shaped recess or chamber 15 between the diaphragm-electrode and the table, which limits the receding or parting movement of the ball, returns it to contact with the electrode, and prevents rebounding.

The described position of the ball-electrode, 20 of course, is one that gives a light initial contact between it and the diaphragm-electrode; but as the table is in the battery-circuit an additional or a second initial contact-pressure is obtained between the ball and the table; 25 hence the variations in the strength of the current are equal to the sum of variations of these contact-pressure, or that between the diaphragm-electrode and the ball and between the latter and the table.

30 Any suitable screw or regulating device, e, may be employed to adjust the table to vary its inclination for altering the degree of initial contact-pressure between the electrodes.

The table may be wholly of metal or other 35 suitable conductor, as indicated in Fig. 3; or it may consist of a carbon block having a groove for the reception of the ball and a metal or other support for the carbon block or plate, as indicated in Figs. 1 and 2. I 40 prefer this last-described form, as it is evident that with the two carbon contacts for the ball the sum of its two initial contact-pressure is greater than when one of them is in contact with metal. In this form of instrument there is, therefore, a ball-electrode 45 loosely supported upon an inclined table or electrode, and in contact with an electrode on the diaphragm. Consequently when the diaphragm is vibrated by sounds spoken or impinging against it the initial contact-pressure 50 of the ball are varied, resulting in changes of resistance of the primary circuit. The ball partakes of the impelling movement or pressure of the diaphragm, and the contact of 55 the ball with the diaphragm is maintained by the inclination of the table E until the diaphragm slows up preparatory to its return-

swing, when the ball moves backwardly more rapidly, by reason of its acquired motion or force, and separates from the diaphragm-electrode, so as to break the primary circuit and interrupt the battery-current; but the continuous backward movement of the ball is retarded by the inclination of the table E, and the ball soon returns to contact with the diaphragm-electrode, re-establishing the primary circuit. 60

I have ocularly demonstrated that with the size of the ball shown breaks occur habitually in rapid succession when words are 70 spoken into the transmitter in an ordinary tone of voice; that for whispering or very low tones of voice the same result is obtained by a much smaller ball. For loud or yelling tones a much larger diameter of ball may be 75 employed; but ordinarily the one shown is the size I use, as by varying the inclination of the table from two to forty-five degrees the same size of ball may be used to produce the result described. 80

By the successive changes of resistance and interruptions of the primary circuit electric currents are induced in the line or secondary circuit, which so operate on the receiver that it reproduces the vocal articulations or other 85 sounds projected into the transmitter.

I have endeavored to ascertain just what phases of a sound or articulation cause breaks in the primary circuit; also, what precise functions the induced currents resulting from 90 the breaks and makes of the primary circuit performed. In these endeavors I have been unsuccessful; but I have ascertained and know that speech transmitted according to my method is reproduced by a receiver with a distinctness 95 exceptional, in that the syllables and words are as clearly separated as in the natural speech, and do not run together.

What I claim is—

The art or method of transmitting articulate speech or other sounds telephonically by 100 induced currents over a secondary circuit, which consists in causing the speech or sounds to vary the resistance as well as to open and close the primary circuit associated with such 105 secondary circuit, substantially as before set forth.

In testimony whereof I affix my signature in presence of two witnesses.

JAMES W. BONTA.
